FIG. 1

FIG. 3

FIG. 2

FIGURE 1 is a perspective view of a tire showing the new design, it being understood that the tread portion shown is repeated throughout the circumference of the tire and that the shoulder design shown is repeated throughout the circumference of the shoulder, the opposite side of the tire being substantially like the side shown;

FIGURE 2 is an enlarged fragmentary plan view of the tread portion of the tire shown in FIGURE 1; and

FIGURE 3 is an axial sectional view taken through the tire substantially on the plane indicated by the line 3-3 of FIGURE 2.

The dominant features of my design reside in the portions shown in full lines.

I claim:

The ornamental design for a tire, substantially as shown and described.
